UNITED STATES PATENT OFFICE.

SAMUEL D. SMITH, OF EAST DEDHAM, MASSACHUSETTS, ASSIGNOR OF ONE-HALF TO
JOHN C. KENNEDY, OF BOSTON, MASSACHUSETTS.

CUSHION-HEEL.

1,114,302.

Specification of Letters Patent. Patented Oct. 20, 1914.

Application filed May 29, 1914. Serial No. 841,699.

To all whom it may concern:

Be it known that I, SAMUEL D. SMITH, of East Dedham, in the county of Norfolk and State of Massachusetts, have invented 5 certain new and useful Improvements in Cushion-Heels, of which the following is a specification.

This invention relates to cushion heels or heel treads of the kind usually known as 10 rubber heels. Such heels are in great demand in spite of their lack of durability. Attempts have been made to increase their 15 wearing qualities but, so far as I am aware, all such attempts have either impaired the resilience of the heels or have resulted in the leaving of cavities which soon get packed with dirt.

The object of my invention is to provide a cushion heel having wear-resisting plugs in 20 those portions of the tread surface which are usually first worn down, the plugs being of a form which present solid wear surfaces that wear well and prevent the picking up of dirt, the whole being so constructed that 25 the elasticity of the heel is not lessened by the presence of the plugs.

To this end, my invention consists in the improved cushion heel or tread which I shall now proceed to describe and claim.

30 Of the accompanying drawings: Figure 1 is a bottom view of an elastic heel-tread embodying my invention; Fig. 2 is a top view of the same; Fig. 3 represents a section on line 3—3 of Fig. 1.

35 The body 12 of the tread, composed of rubber or any of the compositions used for elastic or cushion heels or heel-treads, is shown as formed with holes 13 as usual for the nails which secure the said body to the 40 heel portion of a shoe, or to leather heel-lifts. Such holes may extend entirely or but partially through the body. They constitute no part of this invention. In fact the body may be secured in place by any suitable means. At the rear of the heel, which 45 is the portion that first shows wear, is a row of wear-resisting plugs having solid heads 14 substantially flush with the tread surface. The shanks 15 of the plugs are preferably 50 also solid a portion of their length. The inner end of each plug is flanged as at 16, and the head is of greater diameter than the shank to form a flange 17 which is preferably of greater diameter than the flange 16.

In alignment with the cavity 18 of the plug, 55 the body is formed with a hole or recess 19 extending to the upper surface of the body.

In the manufacture of the article, the plugs are supported by pins rising from the bottom of a mold, said pins fitting the 60 cavities 18 of the plugs which then of course, present their heads 14 upwardly, the material of the body is then caused to fill the mold and to enter the spaces around the shanks between the flanges 16, 17 and then 65 vulcanized. When the article is removed from the mold, the holes 19 are the result of the presence in the mold of the plug-supporting pins mentioned. These holes 19, however, are deliberately formed in the 70 body 12 to perform the service, when the article is in use, of reducing the solidity of the elastic substance above the plugs, to permit the plugs to yield more readily when the user is walking than they could if the 75 body were solid above the plugs. In other words, the holes 19 compensate for hardness of the plugs so that the elasticity of the heel is not impaired by the plugs. Of course, when the body is secured in place so 80 tightly that no air can escape from the holes 19, the confined air causes an additional cushioning effect. No air can escape around the plugs owing to the flanges 16, 17, and the material of the body which is packed between said flanges. Both flanges act to prevent the plug from being forced up into the hole 19. When the weight of the wearer causes the material of the body to be compressed, tending to force the plugs into the 85 body, the fact that the flange 17 is larger than the flange 16 causes the material of the body to be pressed more firmly in between the two flanges.

I am aware that tubular wear-pieces, open 95 at their outer ends, have been embedded in rubber heels, said pieces also serving as washers for heel-attaching nails, but such devices pick up dirt and mar carpets and polished floors, and impair the resilience of 100 the rubber. I am also aware that it has been proposed to provide leather soles with holes and fill or partially fill the holes with solid plugs, but such plugs do not yield because the leather is not sufficiently elastic. And I 105 am also aware that solid plugs have been embedded in rubber soles and heels, the plugs extending entirely through from one surface

to the other of the rubber. Obviously this entirely destroys any cushioning effect of the rubber. I do not claim any of these ideas as within my invention, but

5 What I do claim is:

1. A cushion heel having holes extending upwardly from its tread surface and a plug secured in the lower end of each hole and having a length less than the depth of said

10 holes to permit the heel to be compressed without lessening of the cushioning effect by the plugs.

2. A cushion heel having holes extending upwardly from its tread surface and a plug secured in the lower end of each hole and having a length less than the depth of said

15 holes to permit the heel to be compressed without lessening of the cushioning effect by the plugs, the said plugs having solid

heads at their lower ends and having flanges 20 at their ends.

3. A cushion heel having holes extending upwardly from its tread surface and a plug secured in the lower end of each hole and having a length less than the depth of said 25 holes to permit the heel to be compressed without lessening of the cushioning effect by the plugs, the said plugs having solid heads at their lower ends and having flanges at their ends, the flanges at the inner ends 30 of the plugs being of less diameter than the flanges at the outer ends.

In testimony whereof I have affixed my signature, in presence of two witnesses.

SAMUEL D. SMITH.
